CARTRIDGE FOR OIL FILTERS

Thomas E. Aldham, Providence, R. I., assignor to
Fleming Manufacturing Company, a corpora-
tion of Rhode Island

Application January 27, 1938, Serial No. 187,110

3 Claims. (Cl. 210—131)

This invention relates to an oil filter of the type used in connection with engines which depend for their functioning upon a continual circulation of lubricant; and this invention has for one of its objects the provision of an arrangement whereby should the filtering medium become clogged a supply of lubricant would still be circulated to lubricate parts of the engine.

Another object of the invention is the provision of means to by-pass the filtering medium should the pressure required for passage of the oil through the filtering medium increase to such an extent as to endanger the supply of lubricant to the moving parts of the engine.

Another object of the invention is the provision of a by-pass means in the cartridge which is removed and replenished so as to assure a fresh by-pass means each time the cartridge is changed, and prevent failure of the by-pass closure to direct the oil as desired by reason of fatigue of resilient means usually used for causing such closure.

With these and other objects in view, the invention consists of certain novel features of construction, as will be more fully described, and particularly pointed out in the appended claims.

In the accompanying drawing:

Fig. 1 is a sectional view of a filter casing with cartridge therein illustrating my improved by-pass container within the cartridge;

Fig. 2 is a sectional view on line 2—2 of Fig. 1.

It is considered desirable to provide for a by-pass of a filter in the event the cartridge becomes so clogged that the oil will not readily pass therethrough. Such a by-pass is sometimes provided in the mounting for the filter casing or in the casing in such a manner that it remains continually in such location throughout the life of the mounting or casing. Such a by-pass usually has some sort of a spring or resilient means for operating it. This spring through frequent operation often becomes fatigued and the valve means for controlling the by-pass is permitted to open and the functioning of the filter medium does not play the part which it is intended to perform. Accordingly, I have chosen to locate the by-pass in the cartridge which is intended to be removed from time to time and which serves to protect the lubricating system should the cartridge become clogged or the pressure be increased while at the same time as the cartridge is removed from time to time a fresh resilient closure valve is supplied each time a new cartridge is put in place and the fatiguing and

failure of the closure is eliminated; and the following is a more detailed description of the present embodiment of this invention, illustrating the preferred means by which these advantageous results may be accomplished:

With reference to the drawing, 10 designates a casing of generally cylindrical form having a bulging bottom wall 11 provided with a discharge conduit 12. The side wall of the casing is bulged outwardly as at 13 provided with an inlet conduit 14. A cover 15 is located on the outwardly flanged portion 16 of the side wall which is bolted in place by suitable fastening means 17. A packing 18 exists between the cover and the flange for sealing the cover in position.

A cartridge designated generally 19 is also of cylindrical formation having a bottom wall 20 and a top wall 21 both of which are firmly secured in position on the cylindrical side wall while there is a central opening 22 formed by tube 23 extending axially through the cylinder 19. Filter material 24 is positioned within the cartridge. A resilient spring or handle 25 which engages the cover serves to force the cartridge downwardly on the packing 18 to form a seal between the inlet and outlet conduits.

The top wall 21 in the portion above the central opening 22 is provided with an opening 27 which receives a housing 28 comprising an upper wall 29 having a hole 30 therein which is sealed by a ball 31 urged into engagement with the edges of the opening by a spring 32 engaging the in-turned lips 33 of the side walls 34 and leaving an opening 35 between them. Oil which enters through the conduit 14 passes through the perforations 36 in the cylindrical wall of the cartridge 19 through the filter medium 24 and out through the openings 37 in the tube 23.

The entire volume of the chambers 38 and 39 at the sides and top of the cartridge are full of oil and should the pressure in this volume of oil increase beyond the pre-determined calculated pressure of the spring 32 which forces the valve 31 to closed position, the valve would then be forced inwardly against the spring and the oil would pass through hole 30 through the spring chamber and out through the space 35 through the central opening 22 and out the discharge conduit 12, thus, by-passing the filter medium 24. If, however, the pressure does not exist beyond a predetermined calculated amount, the oil will then pass through the filter medium 24 down to the tube 22 and out through the conduit 12.

Thus, a by-pass is provided which protects the circulating supply of lubricant to the engine 55

and it is so located and carried by the cartridge that it will be removed when the cartridge is removed or changed that a fresh one be substituted therefor, thus replacing the resilient portion of the by-pass before any injury may come to it by reason of fatigue.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

18. 1. A filter cartridge comprising a package of filtering material, a perforated wall surrounding and permanently enclosing said filtering material and having annular imperforate end walls over the ends of said filtering material, a central 20 tubular discharge conduit secured at its ends to said end walls and having perforations and extending through the filtering material for outlet of the filtrate after its passage through the filtering material, a by-pass conduit within said discharge conduit and supported at the upper end of the cartridge to afford a passage of the filtered liquid from the direction of the upper end wall of the cartridge when excessive pressure or clogging of the filtering material occurs, said by-pass 25 conduit comprising a housing having a side wall spaced from the perforated portion of said discharge conduit, upper and lower end walls in said housing each with a central opening therein, a ball valve for engaging the edges of the opening in said upper end wall, and a spring acting between said upper and lower walls of said housing to normally urge said ball into a closed fluid sealed position.
30. 2. A filter cartridge comprising a package of filtering material, a perforated wall surrounding and permanently enclosing said filtering material, annular imperforate top and bottom end walls over the ends of said filtering material, a central perforated tube disposed between said end 35 walls extending through the filtering material

for egress of the filtrate after its passage through the filtering material, a by-pass conduit within said tube and carried by the upper end wall of the cartridge to afford a passage of the filtered liquid from the direction of the upper end wall of the cartridge when excessive pressure or clogging of the filtering material occurs, said by-pass conduit comprising a housing having a side wall spaced from the perforated part of said discharge conduit, upper and lower end walls in said housing 10 each with a central opening therein, a ball valve normally engaging the edges of the opening in said upper end wall of the housing for controlling fluid flow through said conduit, and a spring acting between said upper and lower walls of said housing to normally urge said ball into a closed position. 15

3. A filter cartridge comprising a package of filtering material, a perforated wall surrounding and permanently enclosing said filtering material, a central perforated tube disposed between said end walls extending through the filtering material for egress of the filtrate after its passage through 20 the filtering material, a by-pass conduit within said tube and carried by the upper end wall of the cartridge to afford a passage of the filtered liquid from the direction of the upper end wall of the cartridge when excessive pressure or clogging of the filtering material occurs, said by-pass 25 conduit comprising a housing having a side wall concentric with and spaced from the perforated part of said tube and extending inwardly thereof from the upper end wall of the cartridge, upper 30 and lower end walls in said housing each with a central opening, said upper end wall of said housing being secured to the annular upper end wall of the cartridge and having an opening the edges of which form a seat for a ball valve, a ball valve engaging the edges of said opening in 35 said upper end wall, and a spring acting between said upper and lower walls of said housing to normally urge said ball into a closed position. 40
